No. 52

DESIGN FOR PARLOUR GRATE,

ADAM HAMPTON N.Y.

Patented July 10, 1846.

UNITED STATES PATENT OFFICE.

ADAM HAMPTON, OF NEW YORK, N. Y.

DESIGN FOR A PARLOR-GRADE.

Specification forming part of Design No. 52, dated July 10, 1846.

To all whom it may concern:

Be it known that I, ADAM HAMPTON, of the city, county, and State of New York, have produced a new and useful Design for a Fire-Place Grate; and I do hereby declare the following to be a full, clear, and exact description of the same, reference being had to the annexed drawing, making a part of this specification.

The nature of my invention consists in the production of a design for a grate in the style of architecture of Louis XIV of France.

I make a groundwork of cross-bar style of matting, formed by punching round cavities near together, and thus leaving the crossed lines of the groundwork raised above the punched cavities. This is termed a "matting," and bears some resemblance to some patterns of lace-work; but I do not consider this part as new or material for the object of a patent. Upon the groundwork I build or raise up the ornaments, as I will proceed to describe.

Of the frame of the grate.—In the center of the top is a face surrounded by shell-work above and below, with scrolls from each side. (See *a a*, *b b*, and *c c* in drawing.) *d d* are each pieces of mingled scroll and leafage, which spread entirely across the top of "frame of grate," with the above-named shells, scrolls, face, &c., (except that the corners are turned by scrolls *f f*.) These scrolls are mounted upon other scrolls, which wind down the sides to the leafage pieces *i i*.—By a reference to the drawing it will be noticed that a dragon is entwined with the last-named scrolls, and may be known as *g g*, while the scrolls are known as *h h*. The leafage pieces *i i* are based upon shell and scroll work, which reaches and finishes the base of the frame of grate, the last being entirely surrounded from the base to the shell-work in center of its top with light raised scroll-work. (See *m m m m* in drawing.)

Of the summer piece or center.—This, like the frame, is raised ornament upon a matting, as set forth. The top of this (see *n* in drawing) is a broad span of leafage and shell work rest-

ing upon sides or columns of scroll and leafage, and may be known as *o o* in drawing. Below these are a right and left piece of scroll and leafage, forming a finish to the raised work of the "summer-piece." (See *p* in drawing.) There is a niche in the center, in which it is intended to place a cast-metal statue or other device.

Of the fender.—The center of this is a cluster of scrolls mounted with leafage and that surmounted by shell-work, and may be known as *q* in drawing. *s s*, on each side, are shells centered upon scrolls of a light raised character, and directly over them are scrolls *r r*. The last-named scrolls spread by their connections to the scroll and leafage pieces or ends *u u*. These inclose the shell and leafage pieces centered upon scrolls known as *t t* in drawing. Spreading from *s s* to *t t* are the leafage scrolls *v v*, which terminate the base of the fender.

It will be thus seen that this grate is composed of three parts—that is, a frame of grate, a center or summer piece, and a "fender." These are each a separate piece, and may be used either of them separately or unitedly with ease or convenience and ease.

What I claim to have produced in this design, and wish to secure in Letters Patent, is—

1. The raised ornaments, as described, upon a groundwork of any style, with the same combination or ornaments for a frame of grate, the raised ornaments upon the center or summer piece in the here-shown combination, and the raised ornaments upon the fender, with the shown combination of ornaments.

2. The combining of these together into one grate, consisting of a frame of grate, summer-piece, and fender, the same making up a complete "parlor-grate" of new and original design.

ADAM HAMPTON.
